UNITED STATES PATENT OFFICE.

CHARLES BRAND, OF BASEL, SWITZERLAND, ASSIGNOR TO THE FIRM OF INDUSTRIE-
GESELLSCHAFT FÜR SCHAPPE, OF BASEL, SWITZERLAND.

THREAD-FEED-STOPPING DEVICE FOR SPINNING, TWISTING, AND SIMILAR MACHINES.

1,247,926.

Specification of Letters Patent. Patented Nov. 27, 1917.

Application filed August 4, 1917. Serial No. 184,484.

To all whom it may concern:

Be it known that I, CHARLES BRAND, a citizen of the Swiss Republic, and resident of Basel, Switzerland, manager, have invented a new and useful Thread-Feed-Stopping Device for Spinning, Twisting, and Similar Machines, of which the following is a full, clear, and exact specification.

It is already known, in spinning and twisting machines to cause automatically the stopping of the thread supply when the thread breaks between the draw-in roller and the spindle. For this purpose, all kinds of thread controlling devices are in use. In one of these, the draw-in roller is simply stopped so that the drawing-in action ceases and the supply of thread is thus interrupted. In others, the thread passing around the draw-in roller is deviated by a feeler to one side in such a manner, that it falls off from the roller, and is therefore no longer drawn-in. In other arrangements use is made of gripping and breaking mechanisms, which when the thread breaks, seize and break off the filament supply.

All these devices have various drawbacks, partly in that they act upon the delivery side of the draw-in roller, and not upon the feeding side of it, so that the drawn-in filament remains unbroken on the feeding side and therefore the danger of a further drawing-in of the filaments is not prevented, and partly that they are either unreliable in seizing or clamping and breaking-off of the thread, or they are complicated in construction.

The object of the present invention is a feed stopping device for spinning, twisting and similar machines for interrupting the supply of filament when the thread breaks between the draw-in roller and the spindle, in which the thread passing to the draw-in roller is in case of breakage also deviated to one side of the roller by a feeler, but which is distinguished advantageously from the previously known devices of this kind by the arrangement that the feeler shifts the supplied thread by its lateral deviation within the range of seizing means revolving with the thread draw-in roller, which means seize the thread with certainty and during the further revolution of the roller exert upon the thread which is held fast at the entering point such a pull on the supply

side of the thread that it is forcibly broken 55 on that side, and consequently the further supply of thread is interrupted.

The seizing means consist preferably of one or more obliquely directed catching slots, which are arranged on that side edge 60 of the thread draw-in roller, toward which the thread when broken is deviated by the feeler. It is moreover advantageous to arrange on that side of the thread draw-in roller, toward which the thread when broken 65 is deviated by the feeler, a protecting disk which stands still in operation, in order to prevent any tangling or winding-on of the thread deviated to said side.

The accompanying drawing illustrates an 70 embodiment of the invention as follows:

Figure 1 shows a vertical section through a twisting machine provided with the feed stopping device.

Fig. 2 shows a partial plan view of Fig. 1. 75

Fig. 3 shows a partial front elevation of the machine, with a frame part in section.

Figs. 4 and 5 show the construction of a thread draw-in roller provided with tangle 80 protecting disk.

Figs. 6 and 7 show the construction and support of a feeler.

As usual in twisting machines, the thread α coming from the supply spools, first passes through the guide eye a placed upon the 85 supply side, then passes beneath and above the revolving thread draw-in roller b , from there to the guide pin c placed on the supply side and finally again parallel to the first track between the thread draw-in roller b 90 and the driving support roller d to the spindle or rather to the traveler.

On this track, which is well known, the thread is subjected to the action of a feeler or detector e which acts as a controller for 95 the breaking of the thread. This feeler consists of a wire loop with two limbs e^1, e^2 , of which that marked e^1 , engages the thread behind the draw-in point or on the supply side, while the other one e^2 , rests upon the 100 thread on the running off side or before the draw-in place. Through the tension of the thread during the operation the feeler e with its limbs e^1, e^2 , is held up in the control position in which the thread can take 105 the course above indicated. But if the thread breaks between the thread draw-in roller and the spindle, then the front limb e^2

of the feeler being no longer supported falls down from its higher position into the hanging position, as is illustrated in Fig. 3 for the middle feeler, and the rear limb e^2 of the feeler obviously performs the same turning down movement, and thereby directs the thread supplied to the draw-in roller toward one side of the same.

The thread draw-in roller b is provided at its side edge toward which the thread is deviated on breakage, in the manner shown in Fig. 5 with two obliquely directed catching slots f set diametrically opposite one another. Moreover it is provided at the same side with a tangle protecting disk g which is normally stationary. This latter is supported upon the pivot pin h of the roller b , and rests with a bush k like the corresponding pivot i of the roller in the open bearings m . The tangle protecting disk g is prevented by a stop n from turning on its own account without in any way hindering the turning of the roller b .

If as already stated there occurs a breakage of the thread and the thread passing to the draw-in roller b is deviated by the feeler e , then it comes within the range of one of the slots f of the still rotating roller b and is caught by this latter, and receives through the further rotary movement of the draw-in roller a forward pull, while the thread is held fast at the draw-in place o and is thereby further drawn, so that the thread must break at the guide pin c and thereby the further delivery of thread on the supply side is interrupted. The portion of thread falling sidewise from the roller b cannot tangle itself because it comes to rest on the stationary protecting disk g .

In order to insure upon the re-insertion in its bearings of the draw-in roller b after it has been taken out, that the tangle protecting disk g has its correct position, this latter is provided at one point of its periphery with a weight p (see Figs. 4 and 5) by means of which the disk will always turn automatically into such a position that the stop n is located vertically above the bush k .

On the stopping of the machine which involves the ceasing of the thread tension the feeler e would hang down with its limbs. In order to uphold the feeler in the operative position even when the machine is not working a supporting rod r is provided with fingers s , which rod can be so displaced that the fingers s engage under the limb e^1 of the feeler and thereby hold fast the feeler e in its controlling position.

The construction and the support of each separate feeler e is illustrated best in Figs. 6 and 7. The socket part of the wire loop forming the feeler is inserted in a metal tube t which passes through the bearing m between the respective thread draw-in rollers b , and which is narrowed at its ends

to form bearing openings, in which the feeler is held so as to turn easily. The front feeler limb e^2 possesses at its free end an eyelet for the passage of the thread and the rear limb e^1 possesses a turned-in claw.

The two catching slots on the thread draw-in roller b form a catching or seizing device, but the same effect could also be obtained by means of a single catching slot, or more than two slots might be provided on the roller. Moreover instead of them a catching device of any other kind might be arranged on the thread draw-in roller or be connected thereto to rotate with it.

What I claim is:

1. A thread feed stopping device for spinning, twisting and similar machines, of the kind above referred to, characterized by the combination with a rotating thread draw-in roller of a movable feeler for laterally deviating the thread on breakage, guide means for the thread on the supply side of the draw-in roller and seizing means arranged to revolve with the draw-in roller and to seize the laterally deviated thread, so as to exert during further rotation of the draw-in roller such a pull upon the thread on the supply side that the thread will necessarily be broken on said side and thereby the further supply of thread will be interrupted.

2. A thread feed stopping device for spinning, twisting and similar machines, of the kind above referred to, characterized by the combination with a rotating thread draw-in roller of a movable feeler for laterally deviating the thread on breakage, guide means for the thread on the supply side of the draw-in roller and a catching slot arranged at that side edge of said roller to which the broken thread is deviated, so as to catch and forcibly break the laterally deviated thread on the supply side upon further rotation of the draw-in roller, substantially as described.

3. A thread feed stopping device for spinning, twisting and similar machines, of the kind above referred to, characterized by the combination with a rotating thread draw-in roller of a movable feeler for laterally deviating the thread on breakage, guide means for the thread on the supply side of the draw-in roller, seizing means arranged to revolve with the draw-in roller and to seize and forcibly break the laterally deviated thread on the supply side upon further rotation of the draw-in roller, and a normally stationary tangle protecting disk placed on that side of the draw-in roller to which the broken thread is deviated, substantially as described.

4. A thread feed stopping device for spinning, twisting and similar machines, of the kind above referred to, characterized by the combination with a rotating thread

draw-in roller of a movable feeler for laterally deviating the thread on breakage, guide means for the thread on the supply side of the draw-in roller, seizing means arranged to revolve with the draw-in roller and to seize and forcibly break the laterally deviated thread on the supply side upon further rotation of the draw-in roller, and a self-adjustable, normally stationary tangle 10 protecting disk placed on that side of the

draw-in roller to which the broken thread is deviated, substantially as described.

In witness whereof I have hereunto signed my name this 12th day of July 1917, in the presence of two subscribing witnesses.

CHARLES BRAND.
